UNITED STATES PATENT OFFICE

91,282

DESIGN FOR A TOILET PAPER HOLDER

Merick Reynolds, Los Angeles, Calif.

Application March 24, 1933. Serial No. 47,579

Term of patent 3½ years

To all whom it may concern:

Be it known that I, MERICK REYNOLDS, a citizen of the United States, residing in Los Angeles, in the county of Los Angeles and State of California, have invented a new, original, and ornamental Design for a Toilet Paper Holder, of which the following is a specification, reference being had to the accompanying drawing, forming part thereof.

I claim:

The ornamental design for a toilet paper holder, as shown.

MERICK REYNOLDS.
